United States Patent Office.

JONATHAN M. CLARK, OF NEW YORK, N. Y.

Letters Patent No. 81,983, dated September 8, 1868.

IMPROVEMENT IN STEAM-GENERATORS.

The Schedule referred to in these Letters Patent and making part of the same

TO ALL WHOM IT MAY CONCERN:

Be it known that I, JONATHAN M. CLARK, of the city, county, and State of New York, have invented a new and useful Improvement in Tubular Boilers, of which the following is a full, clear, and exact description, reference being had to the accompanying drawing, forming part of this specification, and in which—

Figure 1 represents a longitudinal section of a boiler, or boiler in part, constructed in accordance with my improvement.

Figure 2, a longitudinal section, on an enlarged scale, of two of the tubes, with their hollow heads, and

Figure 3 a sectional end view of the same.

Similar letters of reference indicate corresponding parts.

This, my improvement, relates to that description of boilers which are made up of a tier or tiers of tubes, arranged one above the other, at, say, a slight angle from the horizon, and communicating with each other, that is, the tubes that lie one above the other, by or through passages at their ends, and combining with such construction separate heads to the tubes, of a square or block-like character, and that butt the one up against the other, to form general close heads to the ends of the boiler made up of tubes, as described.

My improvement on such description of boiler consists in a combination, with the tubes, of enlarged hollow heads, covered externally by cap-plates, and communicating, by orifices made in their side or edges, in a direct manner, the one with the other, and whereby not only are return-pipes or bends dispensed with, to establish a free circulation throughout the tubes, and said heads, which are of a square or block-like character, made to form general close heads to the ends of the boiler, but whereby the circulation is kept up, without exposure beyond the ends of the boiler, the tendency to fouling is reduced, and, by the enlarged opening presented on removal of any one or more of the cap-plates, the greatest facility afforded for clearing out the tubes.

Referring to the accompanying drawing, A A represent the tubes, of which there may be any number in a tier, arranged one above the other, and any number of tiers, side by side in a row. These tubes, that may be of any desired diameter and length, are set inclining upwards from the back to and over the fireplace, and are open at their ends, where they are fitted or provided with enlarged hollow heads B B, having caps or cap-plates a a, of square or parallelogramic form, said caps being secured to the heads by bolts b, and the heads being of such a size or area as that sediment or matter may settle in them, without interrupting free passage through the tubes or the orifices c c, that establish a direct connection between the heads, at either end, in a tier, and by which enlarged capacity of the heads, relatively to the tubes, a large and full exposure of the tubes at their ends is established, for cleaning-out purposes, or simply removing the caps that cover the heads. The enlarged hollow heads B B, with their cap-plates, rest, one upon and against the other, and fit, by annular projections and recesses d d', through intermediate rubber packing e, in steam-tight connection at or around the orifices c c, and may be drawn up tight by nuts f, screwing on to pin-projections g, fast to the one of two adjacent heads, and passing through openings on the other of said heads. The parallelogramic shape of the enlarged hollow heads and their caps serves to give a steady rest of the tubes, the one upon or against the other, and to form close general heads or ends to the boiler.

Where two or more tiers of tubes, arranged side by side, are used, any suitable water-feed connection may be established between them at their base, and steam communication between them at their tops.

What is here claimed, and desired to be secured by Letters Patent, is—

The angular hollow head B, constructed with passages c, for the circulation of water or steam, secured together by pin-projections g and nuts f, and with removable covers a, combined with the tubes A, substantially as shown and described for the purpose set forth.

JONATHAN M. CLARK.
